BEVERAGE CHARGING

John D. Strutzel, Maywood, Ill.

Application June 8, 1935, Serial No. 25,571

1 Claim. (Cl. 226—72)

This invention relates to the subject of filling beverage containers in connection with a process of charging the liquid in the containers after the filling operation and prior to shipment of the containers.

Objects of the invention are to effect more perfect charging, that is, to bring about more exactness and uniformity with reference to the quantity of liquid and predetermined volumes of charging gas placed in each container and to avoid some of the difficulties incident to the filling of the containers with precharged beverages. Another purpose of the invention is to provide improved equipment for rapidly filling and charging the containers and causing complete diffusion of the gas in the liquid.

The improved equipment is illustrated by the drawings, wherein:

Figure 1 is a longitudinal section showing a receiver for beverage containers with connections to charging equipment, and a drive means for rotating the receiver. A beverage container partly in section is shown in the receiver.

Fig. 2 is an enlarged sectional detail illustrating the manner of mounting a rotating tube which conducts gas to a beverage container while the latter is rotated for mixing.

Fig. 3 is a detail view partly in section of one end of a container and valve connections therefor.

Fig. 4 is a view in longitudinal section showing a modification of the equipment illustrated by Fig. 1.

Fig. 5 is a view of the receiver with container chutes associated therewith and in section as indicated by the line 5—5 of Fig. 4.

The construction is used for charging liquid in delivery containers after the uncharged liquid has been placed therein.

The common method of filling shipping containers of the barrel type herein illustrated is to deliver thereto a charged beverage and due to the fact that the liquid is under pressure it is difficult to avoid foaming in the filling operation

and to exactly fill the containers with a specified quantity of the liquid under a predetermined charge. Great care must be exercised in the filling operation to avoid the retention of air in the containers or the expansion of the charged liquid as it enters the containers.

If the air is completely removed from the beverage container and is replaced with CO₂ gas the beverage may be preserved indefinitely against spoilage so long as such conditions are maintained.

By means of the improved equipment it is possible to follow a method of charging by which it is possible to attain uniform and exact results in the product. A container is completely filled with uncharged liquid, driving out all air from the container; then a definite quantity of the liquid is driven out of the container by the charging gas. When that predetermined quantity of the liquid has been removed from the container, the liquid inlet and outlet valves are closed but the gas pressure is maintained while the gas and liquid in the container is agitated to cause the gas to thoroughly permeate the liquid. The agitation is effected by rotating or oscillating the container while the pressure on the gas is maintained. The pressure is maintained constant during the period of agitation but the degree of pressure, rate of agitation and period of agitation are dependent upon the nature of the beverage. Some beverages more readily absorb the CO₂ gas than others. It is also desirable to place in different beverages different volumes of charging gas according to the nature of the beverage. Therefore the pressure applied is varied to suit such requirements and a machine may be timed for different periods of operation and its speed may be altered by use of speed changing gears.

The agitation is maintained for a period of from two to five minutes, depending upon the size and construction of the container and the kind of liquid. The metal barrel containers illustrated in the drawings are provided with baffles or perforated partitions which aid in effecting a rapid intermingling of the gas and liquid.

The equipment provided for carrying out this method of charging consists of an open-ended receiver into which the container slides from a chute and the receiver is mounted on trunnions so that it may be rotated after a container is clamped therein, is filled and the liquid is under gas pressure. Connections are provided for maintaining the gas pressure while the container is in motion.

Figure 1 shows an open-ended cylindrical receiver, or holder 1 for barrel-shaped beverage containers of the type indicated by the numeral 2. Each container is slid from a receiving platform or chute 3 into the receiver with the top end up and is clamped in this position by the hinged member 4 which is slotted to receive a pivoted bolt 5 for guiding a clamping nut 6.

The head 7 of each container is equipped with a plug 8 having a valve 9, at its lower end, which is carried by a valve stem 10. The stem 10 has a

square head 11 which is hollow from the top down to the transverse aperture 12.

A hollow fitting 13 serves as a key for turning the valve by fitting over the square head 11 of the valve stem. The fitting 13 and the plug 8 have a bayonet slot and pin connection 14 which provides for opening the valve when the fitting 13 is inserted into the plug and for closing the valve when the fitting is removed. When the fitting 13 is in place, it provides communication between the interior of the container and filling and charging conduits indicated by the numerals 15 and 16. These conduits are respectively opened and closed by valves 17 and 18 attached to the T end 19 of fitting 13. The conduit 15 is detachable so as not to interfere with rotation of holder 1 and leads to a beverage supply vat, not shown. This vat receives the liquid from mixing vats and the level therein is maintained constant by a float valve; and thus the back pressure in conduit 15 does not vary. When a container is filled to the overflowing point, valve 17 is closed and the conduit 16 is connected to valve 18. Valves 18, 20 and 21 are opened allowing charging gas from cylinder 22 to pass through a pressure regulator 23, valve 21, conduits 24, 25, 26 and 16, valve 18, fitting 13 and valve 9 to the liquid in the container.

The liquid is thus placed under a definite pressure as determined by the setting of pressure regulator 23. Valve 18 is then closed and valve 17 is opened. A definite quantity of the liquid in the container then flows out until the pressure drops to that of the fixed back pressure in conduit 15. Then valve 17 is closed, the valve 18 is reopened and in order to mix the gas and liquid, the receiver 1 and container therein are rotated around trunnion supports for the receiver which may be as illustrated in Figure 1 or in Figure 4.

In Figure 1 the receiver is attached to and supported by shafts 27 and 28. The shaft 27 is supported in bearing 29 and is the power shaft, being connected through belt 30 and reduction gears 31 to an electric motor 32.

Shaft 27 carries a cam 33 which operates a ratchet wheel 34 rigid with a switch operating cam 35. The switch is indicated at 36 and is connected through the conductors 31 to a manually operated switch 38 for the motor. The cam 35 serves to open the switch 36 at the end of a complete rotation of ratchet 34. To close the switch 36, the container 1 is thrown over by hand; thus starting motion of ratchet 34 and moving the cam 35 away from the switch.

The supporting shaft 28 for the container 1 is hollow and extends through the fixed bearings 39. Conduits 25 and 26 are rigid with shaft 28. The rotating conduit 25 is connected to the fixed conduit 24 leading to the gas cylinder by a fitting 40 which carries packing 41 surrounding the end of shaft 25.

At the end of a charging operation, all valves are closed and the fitting 13 is removed from the container. In removing the fitting 13 from the container, it is necessary to turn it sufficiently in the bayonet slot connection to close the valve 9.

The filled and charged container is delivered to the chute or slide 42 beneath the table 43 which supports shaft 28 and the chute 3. The half turn of receiver 1, necessary to discharge the filled and charged container, is not sufficient to close switch 36.

The arrangement, shown by Figures 4 and 5, differs from that illustrated in Figure 1 merely in

the location of the supports for receiver 1 and the fact that the discharge chute for the filled containers is in a different location. In Fig. 4 pivot supports 44 and 45 are at the sides of the receiver and the container may stand upright 5 therein during the filling operation. The bearing member 45 is made hollow so that a handle 1 may be inserted therein for convenience in manually turning the receiver.

The discharge chute 46 is arranged for the 10 delivery of the filled and charged containers on the opposite side from that of the receiving chute. The container 2 has short baffles 47 welded thereon inside of its heads and which aid in the mixing of the liquid and gas during rotation of the receiver 1. The container shown in Fig. 1 has a central perforated division wall 48 for the same purpose. This wall is cut away at 49 so as not to interfere with plug 8. All other parts of the equipment shown in Figs. 4 and 5 correspond to 20 the showing in Figs. 1 to 3 and like numerals are applied to identical parts.

The method of charging and the operation of the machine have been described in connection with the detailed description of the mechanism; 25 but briefly and independently of details of construction, the method of charging is as follows: First, either a barrel which has been completely filled with the uncharged liquid through the bung openings 51 or an empty cask or barrel is slid 30 into receiver 1 from the inclined guide 3 of table 43.

The container is then clamped in the receiver 1 by the clamping members 4 and 6. The fitting 13 is applied to plug 8 and in doing so, valve 9 is opened. In case the container has not been filled, 35 the valve 17 is opened and the uncharged beverage is permitted to flow into container 2, the air being released through a vent, or tap rod hole, such as indicated at 50 in Fig. 1. The valve 17 is closed when the container is filled to the overflowing point and the vent is closed. Then gas is admitted to the container by opening valve 18. After a short interval needed for the absorption of the gas by liquid, valve 18 is closed and valve 17 is opened. This permits enough of the liquid 45 under the gas pressure, to be forced back through the conduit 15 until the pressure thereon is reduced to that of the back pressure in conduit 15. Valve 17 is then closed and valve 18 is opened; thus restoring the gas pressure. The pressure is 50 regulated by the reducing valve or pressure regulator 23.

The receiver 1 is then manually rotated in its bearings enough to cause the cam 33 to shift ratchet 34 far enough to permit switch 36 to 55 close by moving cam 35 out of contact therewith. The receiver is then rotated under power derived from motor 32 through the gearing 31, belt 30 and the drive shaft 27.

The rotation of the container in receiver 1 60 causes the gas to uniformly permeate the liquid in the container after about two to five minutes operation, depending on the character of the liquid and gas pressure, when the cam 35 arrives in position for opening switch 36, stopping the 65 motor. Valve 18 is then closed and the fitting 13 is removed from plug 8. In removing this fitting, it must be turned sufficiently to close valve 9.

By this method of charging the containers 2 after the filling operation and causing the gas 70 to expel a definite quantity of the liquid from a filled container, the beverage producer is assured of the removal of all free air from the containers, and uniformity in the extent to which the product is charged without the danger of losing any 75

of the charge or encountering the uncertainties incident to filling containers with precharged liquid.

I claim:

- 5 A beverage container filling and charging equipment comprising a holder for the containers, connections for liquid filling and applying gas pressure within the container, said connections including valves for admitting gas under pressure

to the container and allowing for the flow of liquid into and out of the container, means for agitating the container while communication is maintained between the container and the source of gas supply under pressure, a motor for driving said agitating means, a switch for the motor and a timing device operated by said agitating means and controlling the operation of said switch. 5
